CLAIM

An ornamental design for a display panel of an electronic device with a computer generated icon, as shown and described.

DESCRIPTION

FIG. 1 shows a front view of a first embodiment of a display panel of an electronic device with a computer generated icon;

FIG. 2 shows a front view of a second embodiment of the display panel of the electronic device with the computer generated icon;

FIG. 3 shows a front view of a third embodiment of the display panel of the electronic device with the computer generated icon; and,

FIG. 4 shows a front view of a fourth embodiment of the display panel of the electronic device with the computer generated icon.

The broken line shown in FIGS. 1-4 are for the purpose of illustrating an electronic device and form no part of the claimed design.

1 Claim, 4 Drawing Sheets
